1 Claim

ABSTRACT OF THE DISCLOSURE

A mail box signal flag comprising an elongate section of close wound spiral wire, one end of which is engaged in an opening in a bracket adhesively mounted on a rural mail box and the other end of which is engaged in a rigid flag which includes a projecting ribbed element for retention under an adhesively secured bracket on the door of said rural mail box.

BACKGROUND OF THE INVENTION

Field of the invention

This invention relates to rural mail boxes and more particularly to signaling devices which may be attached thereto to indicate the opening of the door of the mail box as upon mail being placed therein.

Description of the prior art

Prior art structures of this type usually employ some sort of adjustable mounting device which requires drilling openings in the mail box and the door thereof and which devices generally incorporate a rigid arm pivotally mounted and retained by some means so that it will swing or be moved into visible relation to the mail box upon being released. The prior art devices include spring type mountings for resiliently holding the rod as in Patent No. 2,433,940 and spring actuated devices for moving the flag portion as in Patent No. 3,338,510. Still other patents showing mechanical actuated mail box flags wherein freeing of a pivoted member permits gravity actuated movement and these may be seen in Patents Nos. 3,294,057 and 3,191,855.

This invention eliminates the drilling and bolting on of signal flags. It eliminates the expensive and often complicated mechanical contrivances of the prior art and provides an easier, quicker means for mounting and using a mail box signal flag.

SUMMARY OF THE INVENTION

A mail box signal flag comprising an inexpensive elongate section of coiled resilient material secured at one end in a molded bracket adapted for adhesive attachment to the side of a mail box and temporarily held in horizontal position beside the mail box by a keeper attached to the hinged door of the mail box and having a flag portion movable to a position above the mail box when the elongate portion is freed of the keeper by the opening of the mail box door.

DESCRIPTION OF THE DRAWINGS

FIGURE 1 is a perspective view of a rural mail box with the mail box flag in non-signaling location and broken lines illustrating the same in free or signaling position.

FIGURE 2 is an enlarged plan view of a portion of the mail box and the signal flag mounted thereon and showing the same in signaling position.

FIGURE 3 is an enlarged cross sectional elevation on line 3—3 of FIGURE 1.

FIGURE 4 is an enlarged cross sectional elevation on line 4—4 of FIGURE 1.

2

DESCRIPTION OF THE PREFERRED EMBODIMENT

By referring to the drawings in FIGURE 1 in particular, it will be seen that a rural mail box of the type generally used for rural mail delivery has been illustrated and comprises a box portion 10 having a rounded top portion 11 and a hinged door 12 normally closing an open end of the box 10. The door 12 is hinged on pivots 13 adjacent its lower edge and is normally held in closed relation by a two-part friction catch 14 and 15, the parts being respectively attached to the box and the door as will be understood by those skilled in the art.

The device of the invention comprises a mounting bracket 16 having an elongated flat body section 17 which is adapted to be adhesively secured to the side of the mail box 10. The mounting bracket 16 has a vertical opening 18 therein with a thread pattern specifically arranged to threadably receive one end of an elongated section of closely wound resilient material taking the form of a tight spiral configuration and indicated in the drawings by the reference numeral 19.

The member 19 is of a length sufficient that it extends above the top 11 of the mail box when it is in vertical position as seen in FIGURE 2 of the drawings, and a flag device comprising a tubular portion 20 and a vertically positioned flat flag section 21 is mounted on the upper end of the member 19 with the tight spiral wound configuration of the member 19 threadably engaging the inner diameter of the tubular portion 20 of the flag member. The opposite end of the tubular portion 20 threadably receives and thus secures a projecting rib catch member 22.

By referring to FIGURE 1 of the drawings, it will be seen that the catch member 22 is particularly adapted to be temporarily held by a sidewardly extending notched arm 23 which is carried on and forms a part of a flat secondary bracket 24 as best seen in FIGURE 4 of the drawings.

By referring to FIGURES 3 and 4 of the drawings, it will be seen that the mounting bracket 16 and the secondary bracket 24 are both provided with a layer of suitable adhesive 25 so that they may be readily adhered to the respective body and door portions of the rural mail box, thus making installation of the mail box flag particularly easy.

Those skilled in the art will observe that the elongated spiral wound resilient member 19 may be formed of spring wire of lightweight or of resilient plastic or any other suitable material and that its configuration provides for its threadlike engagement in the mounting bracket 16 and the tubular portion 20 of the flag 21. The entire device may, therefore, be inexpensively formed as of molded high impact resin parts and will perform efficiently in its intended environment.

The above described structure provides a relatively inexpensive and easily attachable mail box signal flag which will unfailing indicate the opening of the mail box door and the attendant positioning of mail therein, thus making it unnecessary for the box owner to make unnecessary trips to the box to determine whether or not the mail has arrived.

Although but one embodiment of the present invention has been illustrated and described, it will be apparent to those skilled in the art that various changes and modifications may be made therein without departing from the spirit of the invention or the scope of the appended claim and having thus described my invention what I claim is:

1. A mail box signal flag comprising an elongate section of closely wound spiral shaped resilient material, a mounting flat bracket having an opening therein en-

gaged on one end of said elongate section of resilient material and a flag threadably engaged on the other end of said elongated section of resilient material, a projecting ribbed catch element on said flag device and a second bracket for attachment to the door of said mail box and including a notched arm for receiving and holding said projecting ribbed catch element whereby said mail box flag is held in retracted position until released by the opening of the mail box door carrying the secondary bracket, said flag device comprises a flat vertically disposed vane like member with a vertically positioned tubular edge section defining the means for threadably receiving at its lower end the end of the elongate section of spirally shaped resilient material, and the means for threadably receiving at its upper end said projecting ribbed catch element.
